UNITED STATES PATENT OFFICE.

GEORGE RAWAK, OF NEW YORK, N. Y.

DESIGN FOR A LADY'S HAT.

Application filed February 28, 1925. Serial No. 12,523. Term of patent 7 years.

To all whom it may concern:

Be it known that I, GEORGE RAWAK, a citizen of the United States, and residing at 1 West 39th Street, in the county of New York and State of New York, have invented a new, original, and ornamental Design for Ladies' Hats, of which the following is a specification, reference being had to the accompanying drawings, forming part hereof.

The figure is a perspective view of a lady's hat showing my new design.

I claim:

The ornamental design for a lady's hat as shown.

GEORGE RAWAK
